CLAIM

The ornamental design for a portion of a panel for a storage container such as a hamper or basket, or the like, as described and shown.

DESCRIPTION

FIG. 1 is a front elevational view of a first embodiment of a portion of a panel for a storage container such as a hamper or basket, or the like, of which the rear elevational view is a mirror image;

FIG. 2 is a top right front isometric view of the portion of a panel of FIG. 1;

FIG. 3 is a front elevational view of a second embodiment of a portion of a panel for a storage container such as a hamper or basket, or the like, of which the rear elevational view is a mirror image;

FIG. 4 is a top right front isometric view of the portion of a panel of FIG. 3;

FIG. 5 is a front elevational view of a third embodiment of a portion of a panel for a storage container such as a hamper or basket, or the like, of which the rear elevational view is a mirror image;

FIG. 6 is a top right front isometric view of the portion of a panel of FIG. 5;

FIG. 7 is a front elevational view of a fourth embodiment of a portion of a panel for a storage container such as a hamper or basket, or the like, of which the rear elevational view is a mirror image;

FIG. 8 is a top right front isometric view of the portion of a panel of FIG. 7;

FIG. 9 is a top left front isometric view of the embodiment of FIGS. 1 and 2 as applied to a hamper;

FIG. 10 is a top left front isometric view of the embodiment of FIGS. 7 and 8 as applied to a basket;

FIG. 11 is a top left front isometric view of the embodiment of FIGS. 5 and 6 as applied to a hamper; and,

FIG. 12 is a top left front isometric view of the embodiment of FIGS. 3 and 4 as applied to a basket.

The broken lines show the boundaries of the claimed design or to show environment related to the claimed design. The broken lines form no part of the claimed design.
